CLAIM

The ornamental design for a pollinator bee emergence nursery, as shown and described.

DESCRIPTION

FIG. 1 is a perspective view of a pollinator bee emergence nursery showing our new design;

FIG. 2 is a front elevational view taken in the direction of arrows II-II in FIG. 1;

FIG. 3 is a side elevational view taken in the direction of arrows III-III in FIG. 2;

FIG. 4 is a side elevational view taken in the direction of arrows IV-IV in FIG. 2;

FIG. 5 is a top plan view taken in the direction of arrows V-V in FIG. 3;

FIG. 6 is a bottom plan view taken in the direction of arrows VI-VI in FIG. 3;

FIG. 7 is a rear elevational view taken in the direction of arrows VII-VII in FIG. 4;

FIG. 8 is a partial sectional view taken along line VIII-VIII in FIG. 2;

FIG. 9 is a partial sectional view taken along line IX-IX in FIG. 3; and,

FIG. 10 is a reduced-scale perspective view comparable to FIG. 1 except partly exploded.

The broken lines in the drawing represent environmental subject matter that forms no part of the claimed design.

1 Claim, 10 Drawing Sheets
